UNITED STATES PATENT OFFICE

ARTHUR E. SMALL, OF OAK PARK, ILLINOIS, ASSIGNOR, BY MESNE ASSIGNMENTS, TO
P. H. MURPHY COMPANY, OF NEW KENSINGTON, PENNSYLVANIA, A CORPORA-
TION OF PENNSYLVANIA

RAILWAY-CAR-ROOF STRUCTURE

Application filed April 19, 1926. Serial No. 103,070.

The accompanying drawings illustrate the preferred form of the invention, though it is to be understood that the invention is not limited to the exact details of construction 5 shown and described, as it is obvious that various modifications thereof within the scope of the claims will occur to persons skilled in the art.

My device relates to railway box cars and 10 consists in providing means for moving heavy cargoes in and out of the car and to desired positions within the car.

It is common practice to throw a rope or 15 chain over one of the carlines or purlins of a box car to raise the lading, but the ordinary roof frame of a car is not designed to resist the stresses imposed thereby, thus frequently causing distorted and leaky roofs.

One of the objects of the invention is to 20 strengthen certain carlines of the roof structure to enable them to resist the stresses caused by lifting the lading and to adapt them to accommodate means for removably attaching load lifting devices to such parts.

25 In some cars the roof structure comprises carlines spanning the distance between the opposite side plates with purlins extending longitudinally of the car and attached to the carlines which support metallic roof sheets 30 spanning the space between the adjacent carlines. These roof sheets are sometimes secured to the carlines making what is known as a rigid roof and sometimes positioned loosely between the carlines making what is 35 known as a flexible roof. Sometimes the carlines are eliminated and the roof sheets are so formed and perhaps strengthened that they perform the functions of the usual carline, so the term "carline" as used in this 40 patent means that structure which performs the functions of a carline whether a separate member or an integral part of the sheet or sheets forming the roof proper of the car. It is customary to strengthen the roof framing 45 of the car by providing a plurality of purlins at spaced intervals between the side plates which extend longitudinally of the car and are secured to the carlines, thus forming a framework. Such framework is particu- 50 larly desirable in flexible steel roofs where

the roof sheets are spaced apart from the carlines and do not act as gussets to resist the stresses tending to distort the roof in a horizontal plane. My invention may be modified so that it will be applicable to any type of 55 freight car roof.

The amount of strength which a load lifting device imparts to a carline (or other roof member) may not be sufficient to enable the carline to sustain certain heavy loads; therefore, in some cases it may also be necessary to increase the strength of the carline itself (or other frame member). This may be accomplished by making it of heavier material or by shaping the material differently. 60 Another object of the invention is to provide a plurality of relatively strong and weaker carlines arranged to accommodate a plurality of duplicate roof sheets, and, furthermore, to provide the stronger carlines with 65 means for attaching load lifting devices without affecting the duplicity of the roof sheets.

In the drawings:

Fig. 1 shows a part of a railway car with 70 my invention applied thereon.

Fig. 2 is a section on line 2—2 of Fig. 1.

Fig. 3 shows how the carline is increased in 75 depth to accommodate the load lifting device.

Figs. 4 and 5 show the relation of the dif- 80 ferent depth carlines and the roof sheets.

Figs. 6 and 7 show a modified construction.

Fig. 8 shows the construction and device 85 applied to a rigid type of roof.

Fig. 9 is a detail of the device.

The roof illustrated in Figs. 1—5, inclusive, 90 comprises a plurality of carlines 2 spanning the distance between the opposite side plates 3 having their extremities secured thereto. These carlines are of inverted channel section with opposite side walls 4—4, an upper portion 5 and laterally extending flanges 6. The roof sheets 7 span the distance between the carlines and have their edges spaced apart from the carlines so that the 95 roof sheets may move relative to each other and to the roof framing. A cap 8 is provided to weather-proof the space between the carline and the roof sheets. These roof sheets may extend between the opposite side plates 100

of the car or may extend from a side plate to the ridge or center line of the car.

A plurality of longitudinally extending purlins 9 support the roof sheets and are supported by the carlines. In an ordinary roof 5 the purlins extend uninterruptedly below the carlines and are suspended therefrom by bolts or other means, as shown in Fig. 2. In the carlines that are to sustain the load lifting 10 device the side walls 4 are extended to provide a deeper and, consequently, stronger carline (as shown in Fig. 3) and the purlins are interrupted and are supported by the lateral extending flanges 6 and are preferably se- 15 cured thereto.

A device 10 is positioned entirely within the inverted channel and has its opposite ends secured to the opposite side walls 4 of the carline and a space 11 is provided above the device 10 and below the upper portion 5 of 20 the carline so that a load lifting device may be attached thereto by passing a rope or chain through this opening or passing the nose of the hook through it. The lower part of this 25 device is provided with oppositely disposed lateral flanges 12 to accommodate "ice tongs" or other such load lifting device. Both the carline and the devices are positioned entirely above the lower side of the purlins 9 so 30 as not to interfere with the loading capacity of the car. This device also strengthens the carline by acting as a spreader because when a channel section beam begins to deflect the opposite side walls depart from their vertical 35 plane, or in other words, the channel spreads apart or opens up, as it is called. The device is a strut-tie and prevents the walls of the channel from deflecting either toward or away from each other. This device, therefore, 40 serves the dual purpose of strengthening the roof member to which it is attached and provides means for attaching the load lifting device.

The device may be riveted into place with 45 rivets of less shearing strength than the ultimate strength of the carline so that the device will be pulled away from the carline before the carline is distorted. This to minimize the damage when excessive loads 50 are applied to the device.

The greater the inside height of the car the better as the height from the rail is limited by the tunnel and bridge clearances, particularly at the eaves, therefore, a roof 55 structure must be very shallow. In order to obtain the required strength for certain loads in such a shallow carline it may be necessary to provide other reinforcements. For such necessity I add the reinforcements 60 13 which are located entirely within the inverted channel carline for reasons already enumerated.

Fig. 4 shows an arrangement wherein the 65 relatively deep and shallow carlines are positioned alternately, while Fig. 5 shows a

plurality of shallow carlines positioned between the deeper carlines.

Figs. 6 and 7 show a construction wherein the carlines 2 are all of the same depth and width (in fact, preferably duplicates). Certain of the carlines are reinforced by a separate member 20 which, however, is not of sufficient depth to interfere with the cubical capacity of the car; in other words, it does not extend below the lower surface of the purlins. This member may be secured to the carlines in such a manner as to form a unitary beam. In the construction illustrated the beam or reinforcement 20 is suspended from the carlines by a plurality of 75 straps 21. The particular advantage of this arrangement is that it does not interfere with the standard construction of the roof, and, furthermore, there are no exterior rivets 80 which might cause leaks.

Fig. 8 shows my device and arrangement applied to a rigid type of roof wherein the roof sheet 30 overlaps and hugs the carline 2 and the other roof sheet 31 overlaps the first mentioned roof sheet as well as the carline. The clamp 32 secures the two sheets and the carline together and is held in place by a rivet or a pin 33. The load lifting device 10 is applied to one of the carlines in a similar manner to that described above, 90 which carline is preferably extended to the lower surface of the purlins.

Fig. 9 shows a detail of the load lifting device 10.

The load lifting device disclosed herein 100 is disclosed and claimed in my copending application Serial 103,069 filed April 19, 1926; furthermore the broad feature of a car roof 105 comprising a plurality of carlines some of which are relatively strong is disclosed in claim in said copending application Serial 103,069 filed April 19, 1926.

I claim:

1. In a car roof construction, an inverted channel carline with its extremities secured to the opposite side plates of the car, a purlin extending normally on each side of said carline and supported thereby and secured thereto, roof sheets supported by the purlins on opposite sides of the carline, means to weatherproof the juncture between the sheet and the carline, and a device positioned entirely within the channel carline and secured thereto arranged to accommodate a load lifting device.

2. In a car roof construction, an inverted channel carline with its extremities secured to the opposite side plates of the car, a purlin extending normally on each side of said carline and supported thereby and secured thereto, roof sheets supported by the purlins on opposite sides of the carline, means to weatherproof the juncture between the sheet and the carline, and a device positioned entirely within the channel carline and secured there- 120 125 130

to arranged to accommodate a load lifting device, both the carline and the device being entirely above the lower side of the purlins.

3. In a railway car, the combination of an inverted channel carline comprising a web and spaced apart walls, and a device forming a strut-tie between said walls, which device also provides a place for attachment of a load lifting device.

10 4. In a railway car, the combination of an inverted channel carline comprising a web and spaced apart walls, means to reinforce the carline located within the channel of the carline, and a device forming a strut-tie between said walls, which device also provides a place for attachment of a load lifting device.

20 5. In a railway car, the combination of a plurality of relatively deep carlines, a plurality of relatively shallow carlines, and purlins extending between the relatively deep carlines and below the relatively shallow carlines.

25 6. In a railway car, the combination of a plurality of carlines, and purlins extending between some of said carlines and below other of said carlines.

30 7. In a railway car, the combination of a plurality of relatively deep carlines, a plurality of relatively shallow carlines, and purlins extending between the relatively deep carlines and below the relatively shallow carlines, the said relatively deep carlines provided with means to accommodate a load 35 lifting device.

40 8. In a railway car, the combination of a plurality of carlines, and purlins extending between some of said carlines and below other of said carlines, the first mentioned carlines provided with means to accommodate a load lifting device.

45 9. In a railway car, the combination of an inverted channel carline comprising a web, spaced apart walls and flanges at the lower margins of the walls, a device forming a strut-tie between said walls, which device also provides a place for attachment of a load lifting device, and purlins supported by said flanges.

50 10. In a railway car, the combination of an inverted channel carline comprising a web, spaced apart walls and flanges at the lower margins of the walls, means to reinforce the walls located within the channel of the carline, a device forming a strut-tie between said walls, which device also provides a place for attachment of a load lifting device, and purlins supported by said flanges.

ARTHUR E. SMALL.
